ROBERT CUSHMAN, OF PAWTUCKET, AND JOHN R. DENNIS, OF
CENTRAL FALLS, RHODE ISLAND

Letters Patent No. 84,346, dated November 24, 1868.

IMPROVED POUNCE-HOLDER.

The Schedule referred to in these Letters Patent and making part of the same.

To all whom it may concern:

Be it known that we, ROBERT CUSHMAN, of Pawtucket, and JOHN R. DENNIS, of Central Falls, in the county of Providence, and State of Rhode Island, have invented a new and improved Paper-Smoothener; and we do hereby declare that the following is a full, clear, and exact description thereof, which will enable others skilled in the art to make and use the same, reference being had to the accompanying drawings, forming part of this specification.

Figure 1 represents a side view, partly in section, of our improved paper-smoothener.

Figure 2 is an end view of the same.

Similar letters of reference indicate corresponding parts.

This invention relates to a new instrument for closing the pores of paper after the same have been opened by an eraser, so that the ink may not run on such parts of the paper where erasures have been made.

The invention consists of a handle, to which a bag is fastened that contains rosin and chalk, or any other material, in a powdered state, by which the pores will be closed.

A, in the drawing, represents a handle, made of wood or other suitable material, of suitable size and form.

B is a small bag, made of suitable fabric, and containing powdered rosin and chalk, or other equivalent material. This bag is fastened in suitable manner to one end or portion of the handle.

In the drawing, it is represented as being fitted into a cavity formed in the handle, to the sides of which it is glued or otherwise secured.

When the bag, after a piece of writing has been erased, is drawn over the erased portion, so much of the powder is discharged from the bag, that the pores of the paper will, by the powder, be closed, so that subsequent writing will appear clear and clean on the erased portion.

Having thus described our invention,

We claim as new, and desire to secure by Letters Patent—

As a new article of manufacture, a paper-smoothener, consisting of the handle and bag, substantially as herein shown and described.

The above specification of our invention signed by us, this 16th day of October, 1868.

ROBERT CUSHMAN.
JOHN R. DENNIS.
